F. DAVISON, OF RICHMOND, VIRGINIA.

Letters Patent No. 80,150, dated July 21, 1868.

IMPROVED NAIL-MACHINE.

The Schedule referred to in these Letters Patent and making part of the same.

TO ALL WHOM IT MAY CONCERN:

Be it known that I, F. DAVISON, of Richmond, in the county of Henrico, and in the State of Virginia, have invented certain new and useful Improvements in Nail and Tack-Machines; and do hereby declare that the following is a full, clear, and exact description thereof, reference being had to the accompanying drawings, and to the letters of reference marked thereon.

The nature of my invention consists in an oscillating feeding-apparatus on a nail-machine, by which the plate from which the nails are cut feeds itself, and by its vibrating or oscillating motion gives proper taper to the nail, and also in the punch for making the head of the nail.

In order to enable others skilled in the art to make and use my invention, I will now proceed to describe its construction and operation, referring to the annexed drawings, which form a part of this specification, and in which—

Figure 1 is a side view,

Figure 2 a plan view, and

Figure 3 a side section of the nail-machine.

Figure 4 a side view, and

Figure 5 a bottom view of the feeder.

A represents the body or frame of the machine, resting on legs B B, and made of any material suitable, and of any dimensions required.

The shaft a, in the rear end of this frame, has its bearings in the sides thereof, and is provided on its centre with a cam-wheel, C, and its ends extending through the sides of said frame, have cog-wheels D D thereon, one of them being, in addition, provided with a crank, E, for operating the machine.

F is a connecting rod, one end of which is round, and surrounds the cam-wheel C, and the other is pivoted to the slide G, which slide runs on flanges b b on the inside of the frame. The cutting-knife c is placed horizontally on this slide, and securely fastened thereto, so that by turning the crank E, said knife is moved backward and forward.

On the outside of the frame A are cogged wheels H H, which are so placed as to work into the cogged wheels D D, already described as being on the ends of the shaft a. The wheels H H are provided with crank-pins d d, to which the connecting-rods I I are attached, said rods connecting with the slides J J, which slides run on the sides of the frame, and extend into wings K K on the same, so that by the turning of the crank E, these slides move alternately backwards and forwards, the object of which will be hereafter described.

On the front end of the frame, and in front of the cutting-knife c, is a cross-bar, L, to the rear side of which an angular bar, e, is secured in such a manner as to form a slot between said bar and cross-piece. In the slot thus formed the lower end of the tube M is pivoted, said tube being constructed with arms N N extending on each side above said angular bar, which arms have gauge-screws f f at their ends.

In this tube the plate g, from which the nails are to be cut, is inserted, and its own weight carries it downward, thus making it self-feeding.

On the rear side of the cross-bar L is a stationary knife, h, so arranged that the metal plate g, in descending, comes close along said knife, and the movable knife c will come close up under it.

Under the movable cutting-knife c is a guide, i, extending forward on to the roller O, which latter has female dies on its periphery, and is secured on a shaft, m. This shaft has its bearings in the sides of the frame A, and is turned by means of a ratch-wheel, P, on the same, and spring-pawl k attached to the lever Q. This lever being connected with the rod F, by means of the pitman-rod R, it will be seen that the motion of said rod F also turns the roller O.

Above and a little forward of said roller is another roller, S, which has male dies on its periphery corresponding to the female dies on the roller O, and is secured to a shaft, n, which has its bearings in slots on the frame A, and against the adjustable slides T T in the same.

Under the cross-bar L is a spring, l, which extends forward over the roller O, till near the point where it meets the roller S.

On the upper sides of the slide J, bent arms X extend forward, and when said slides alternately move forward, one of these arms strikes the gauge-screw f on the arm N, thus tipping the tube M over, thereby giving a slanting position to the plate g, so that when the same is cut off it has the proper taper for a nail.

The plate g falls down of its weight on the guide i, the movable knife c, in conjunction with the stationary knife h, cuts it off and carries it forward under the spring l, which latter deposits it in one of the dies on the roller O; a die on the roller S immediately closing in on the same, the nail is held firmly between these dies. In this position the head is made by a punch, Y, which extends through the side of the frame A, into the wing K, where its bevelled end o is struck by the bevelled end of the slide J, pressing the end of the punch up against the rollers O and S, and thus forms the head of the nail. A small spring, p, which catches in a notch on the end o, brings the punch back away from the rollers as soon as the slide J moves backward. A similar punch, T, is on the other side, so that one nail is made with the head on one side of the machine, and the next on the other, corresponding with the oscillating motion of the tube M.

This machine makes edge-pressed nails, and to make side-pressed nails it is only necessary to place the roller S perpendicularly above the roller O, when the cutting-knife c will itself deposit the nails in the dies sideways, instead of letting the spring l deposit them, the pressure of said spring turning them on the edge.

Having thus fully described my invention, what I claim as new, and desire to secure by Letters Patent, is—

1. The combination of the channelled plate-holder M, slotted angular bar E, and vibrating-arms N N, all constructed, arranged, and operating substantially as and for the purposes herein set forth.
2. The combination of the sliding inclines X X, adjusting-screws f f, vibrating-arms N N, and angular bar E, to adjust the plate at different angles, substantially as and for the purposes herein set forth.
3. The combination of the channelled plate-holder M, slotted angular bar E, vibrating-arms N N, and knives C c; to produce a wedge-shaped blank, in the manner specified.

In testimony that I claim the foregoing, I have hereunto set my hand, this 3d day of June, 1868.

F. DAVISON.
